(21) Appl. No.: **29/327,314**

The ornamental design for a menu command button for a touch-based user interface for a display screen, as shown and described.

(22) Filed: **Nov. 4, 2008**

DESCRIPTION

(51) **LOC (9) Cl.** **14-04**

FIG. 1 is a front view of a first embodiment of a menu command button for a touch-based user interface display screen showing the ornamental design thereof in accordance with the present invention;

(52) **U.S. Cl.** **D14/485**

FIG. 2 is a front view of a second embodiment thereof, but shown separately without the broken line environment for clarity of illustration;

(58) **Field of Classification Search** D14/485,

FIG. 3 is a front view of a third embodiment thereof, but shown separately without the broken line environment for clarity of illustration;

D14/486, 487, 488, 489, 490, 491, 492, 493,

FIG. 4 is a front view of a fourth embodiment thereof, but shown separately without the broken line environment for clarity of illustration; and,

D14/494, 495; 348/14.03, 14.14, 14.15,
348/569; 725/41, 43, 52, 53; 345/902, 951,
345/952, 955, 960; 715/793, 799, 808, 809,
715/810, 825, 828, 835, 838, 840, 841, 842,
715/843, 861, 864, 867, 974, 975, 977, 833,
715/215, 246, 700, 703, 712, 716, 719, 721,
715/727, 739, 771, 781, 783

FIG. 5 is a front view of a fifth embodiment thereof, but shown separately without the broken line environment for clarity of illustration.

See application file for complete search history.
